UNITED STATES PATENT OFFICE.

PERCY E. WAITE, OF HUTCHINSON, KANSAS.

GAME.

Application filed April 17, 1924. Serial No. 707,283.

To all whom it may concern:

Be it known that I, PERCY E. WAITE, a citizen of the United States, residing at Hutchinson, in the county of Reno and State of Kansas, have invented certain new and useful Improvements in a Game, of which the following is a specification.

This invention relates to new and useful improvements in games and has for its principal object to provide a device of the above mentioned character, which will afford amusement of the highest degree and is preferably in the form of a puzzle.

A still further object of the present invention is to provide a game of the above mentioned character, which will not only require the exercising of a great degree of skill on the part of the person playing the game but will also require the proper placing of the several parts comprising the game in order to carry out the objects of the invention.

A still further object of the present invention is to provide a game of the above mentioned character, wherein the same comprises a plurality of cooperating units and an objective, the objective being placed at a predetermined position, and the units being adapted for assembly in such a manner as to have the last unit receiving the objective.

A still further object is to provide a game of the above mentioned character, wherein the units when assembled will simulate a snake.

A further object of the invention is to provide a game of the above mentioned character, which is simple in construction, inexpensive, strong and durable and further more adapted for the purposes for which it is designated.

Other objects and advantages of this invention will become apparent during the course of the following description.

In the accompanying drawing forming a part of this specification and in which like numerals designate like parts throughout the same:

Figure 1 is a plan view of my improved game showing the same in an assembled position with the objective in engagement therewith.

Figure 2 is a detail perspective view of one of the units, and

Figure 3 is a detail perspective view of the objective piece.

In the drawing wherein for the purpose of illustration is shown the preferred embodiment of my invention, the numeral 1 designates one of the units forming a part of the present invention and each unit is substantially of an irregular configuration in the manner clearly illustrated in the drawing. As many units may be provided as is desired and the same are further so arranged as to cooperate with each other so that when the units are assembled a figure of a predetermined design may be formed. In the present instance I have shown the figure as representing a snake, although it is to be understood that any other animal may be represented. The objective piece is illustrated at 2 with reference more particularly to Figure 3 of the drawing and as shown therein, any suitable indicia may be placed thereon to render a game more interesting. The units and the objective piece are preferably formed of cardboard although any other suitable material may be substituted therefor and I do not wish to limit myself to the particular kind of material to be used.

In playing the game, the objective piece 2 is placed at a predetermined point on a table or other game board and the object of the game is to form the figure by placing the units comprising the same in cooperative relation so that the last unit placed on the figure, and in which in the present instance represents the head of the snake and is designated by the numeral 3 will have its mouth receiving the objective piece 2 in the manner clearly shown in Figure 1. The first unit to be placed on the table is the tail 4 and the smaller end thereof forms the starting point for the game. The several units are then placed into cooperative relation with each other, it being understood that the proper unit is to be placed adjacent each other so that the same will have their adjacent edges meeting and being of the same width and when the last unit or head section 3 is placed on the table, an effort is made to raise the unit so that the head will receive the objective piece 2. The units may be assembled in various configurations to simulate the various movements of a snake and as heretofore stated, as many units may be provided as is desired.

A game of the above mentioned character, requires the exercising of skill and ingenuity on the part of the person playing the same
